(57) **CLAIM**

The ornamental design for a vehicle front door insert, as shown and described.

DESCRIPTION

FIG. 1 is a front right perspective view of a vehicle front door insert according to the invention, a mirror image thereof, is claimed but not shown.

FIG. 2 is a front left perspective view thereof.

FIG. 3 is a rear left perspective view thereof.

FIG. 4 is a front view thereof.

FIG. 5 is a rear view thereof.

FIG. 6 is a left side view thereof.

FIG. 7 is a right side view thereof.

FIG. 8 is a top view thereof; and,

FIG. 9 is a bottom view thereof.

The broken lines illustrate portions of the vehicle front door insert which form no part of the claimed design.
